MARINE VESSEL

Richard W. Davis, Miami, Fla.

Application October 6, 1941, Serial No. 413,840

3 Claims. (Cl. 115—20)

My invention relates broadly to new and useful improvements in marine vessels and more particularly to that type of vessel having a rotary hull.

An important object of my invention is the provision of a vessel capable of obtaining a high rate of speed by reason of a rotating hull portion which tends to lift itself upon the surface of the water when the vessel is under way in a manner to substantially eliminate both the head and drag resistance which greatly impedes the progress of vessels of other construction.

Another object of my invention is the provision of a vessel of the above-mentioned character that is uniquely constructed to accomplish the above results in an efficient and efficacious manner, which construction is at once durable and light to permit a maximum speed to be obtained.

Still another object of my invention is the provision of a vessel of the above-mentioned character having a sufficient capacity to accommodate both passengers and freight which operates to reduce the volume of water displaced by the vessel as the speed is increased.

Other objects and advantages of my invention will be apparent during the course of the following description.

In the drawings, forming a part of this specification and wherein like numerals are employed to designate like parts throughout the same,

Figure 1 is a longitudinal sectional view of a vessel embodying my invention.

Figure 2 is a transverse sectional view taken on the line 2—2 of Figure 1.

Figure 3 is a vertical sectional view taken on the line 3—3 of Figure 1.

Figure 4 is a fragmentary side elevation of the hull.

Figure 5 is a side elevation of a modified form of the invention.

Figure 6 is a transverse sectional view thereof taken on the line 6—6 of Figure 7.

Figure 7 is a vertical sectional view taken on the line 7—7 of Figure 6.

Figure 8 is a fragmentary vertical sectional view taken on the line 8—8 of Figure 7 and

Figure 9 is a fragmentary vertical sectional view taken on line 9—9 of Figure 7.

In the accompanying drawings, wherein for the purpose of illustration, is shown a preferred embodiment of my invention, the numeral 10 designates a substantially disk-shaped hull adapted to be disposed in an upright position in the water and with a portion of the periphery submerged below the surface thereof. The hull

comprises a peripheral band portion 11 the opposite sides of which are closed by integral frustoconical shaped side walls 12 and 13. Each of the side walls is provided within a central opening 14 and the portion of the walls enclosing the openings are joggled inwardly, as at 15, to receive the essentially circular plates 16 and 17. It is essential that a water-tight union be effected between the side plates and the hull and that the hull be permitted to rotate independently of the plates. Each of the plates is, therefore, provided with a bearing 18 of U-shaped construction in cross section which snugly but slidably embraces the periphery thereof. Retaining rings 19, having the same internal diameter as the openings 14, are applied to the outside surface of the side walls and fixedly held in association therewith by screws 20, or the like. Thus, the joggles 15 of the hull and the retaining rings 19 cooperate in holding the bearings 18 fixedly associated with the hull and the bearings permit the periphery of the plates 16 and 17 to move relative thereto during the rotation of the hull about its axis.

A transversely extending inner platform or deck 21 is arranged in bridging relation with the plates 16 and 17 and the side edges thereof are fixedly secured to the plates substantially below their horizontal diameters by the angle-iron supports 22. An essentially heavy motor 23 is suspended centrally from the platform by the brackets 24 and the base of the motor includes a carriage 25 positioned between the inturned upper flanges 26 of the laterally spaced annular rails 27 extending around the inner periphery of the hull. Rollers 28 extend laterally from the opposite ends of the carriage and below the overhanging flange 26 of the tracks. A suitable trap door 9 is provided in the deck 21 to permit access to be had to the motor from a position on the deck. As the hull is caused to rotate, the relatively great weight of the motor hanging from the platform 21 will hold the side plates 16 and 17 stationary and the rollers carried by the motor carriage will traverse the tracks 27.

In order that access may be had to the interior of the hull I have provided a door 29 in the side plate 17. The door is located above the deck 21 and the marginal edge thereof overlies the door opening to provide an essentially sealed connection therebetween. Essentially small platforms 30 are mounted on the outer face of the side plates 16 and 17 by the angle-irons 31 and the brackets 32. Each of the outer platforms is located in alignment with the inner deck 21 and each preferably extends the full width of the plate to

provide a maximum supporting surface. Each of the outer platforms is provided with a railing 33 which extends along the outer edge thereof and along each end to prevent a person from falling off of the platform. Each of the side plates is also provided with windows, the plate 16 being provided with an essentially large window 34 and the plate 17 being provided with a pair of essentially small windows 35 arranged at opposite sides of the door 29. In order that persons standing on the deck 21 within the hull may see ahead of the vessel, I have provided reflectors 36 which project from the sides of the hull rearwardly of each of the windows. Thus, a person within the hull may look directly through any of the windows to view the water at either side of the hull or he may look angularly through the window and into the reflectors to obtain a view of the water ahead of the vessel. Each of the outer platforms is here illustrated as being provided with a flag staff 37 upstanding from the forward end thereof, which staves carry suitable flags 38.

In order that the hull may be driven through the water, I provide an outer framework which connects with the platforms 30 and extends rearwardly longitudinally of the hull. The framework includes a yoke 39 having the end of each arm portion thereof extending along and connected to the underside of each of the platforms 30. As best illustrated in Figure 2, the yoke is spaced substantially from the hull for its entire length and is normally disposed slightly above the water level. A U-shaped member 49 connects with the yoke at substantially its middle and extends angularly downwardly therefrom below the surface of the water. A rudder 41 is mounted at the end of the U-shaped member 49 and includes oppositely extending transverse arms 42 and 43 connected to a pilot wheel 47 by the cables 44 and 45 which extend through the member 49 and yoke 39 and into the hull below the deck 21. After the cables enter the hull they are conducted by suitably arranged pulleys 46 to the steering or pilot wheel 47 supported above the deck by a suitable standard 48.

The drive shaft of the motor is provided with a gear 49 which meshes with a gear 50. The gear 50 is carried by an idler shaft which is journaled for rotation in the vertical bore of a bracket 51 extending from the engine block above the drive shaft and the upper end of the idler shaft carries a gear 52. A second idler shaft 53 extends through the stuffing box 54 provided in the side plate 17 below the platform 30 and the opposite ends thereof carry outer and inner gears 55 and 56. The inner gear 56 is driven by a gear 57 carried by the countershaft 58, which shaft is journaled for rotation in the bearing supports 59 and is provided with a gear 60 at its lower end which meshes with the gear 52. The shafts 61, 62 and 63 are mounted for rotation in the bearing brackets 64 carried by the yoke 39, the shaft 61 being provided with a gear 65 meshing with the outer gear 55. The shaft 61 is connected to the shaft 62 by universal connection 66 and the shaft 62 is connected with the shaft 63 by universal connections 67.

The diverging ends of the essentially V-shaped propeller support 68 are journaled to the middle of the yoke 39 for swinging movement about a horizontal axis. The apex of the propeller support is bent downwardly, as at 69, and receives the propeller bearing 70. The propeller 71 is journaled for rotation in the bearing 70 and con-

ncts with a driven shaft 72 by a universal connection 73. The opposite end of the driven shaft is rotatably supported by a yoke 74 the ends of which yoke are pivoted to the supporting arms 75 extending from the yoke 39 intermediate the connecting ends of the propeller support 68. Power is transmitted to the driven shaft by a beveled gear 76 fixedly carried by the shaft 63, the beveled gear being disposed in meshed relation with a beveled gear 77 fixedly secured to the adjacent end of the shaft 72. Thus, actuation of the motor will cause the shaft 72 to be rotated to drive the propeller.

Tests have developed that the vessel may be successfully propelled by the use of either a marine or aerial propeller. In the one case the supporting arm 68 must extend below the surface of the water so that the marine propeller may operate and in the other case the arm must extend substantially above the surface of the water so that the aerial propeller may operate. As hereinabove-described, the propeller support is pivotally associated with the yoke 39 and I have provided stationary segmental plates 78 adjacent the pivoted ends thereof which are provided with a series of spaced arcuately arranged openings 79 adapted to receive a bolt which extends through an aligning opening in the propeller support for holding the same in a selected angular position. As the propeller support is pivoted angularly, the shaft 72 will pivot therewith and the beveled gear 77 carried by the shaft will move relative to the beveled gear 76 in a manner to at all times remain in meshed engagement therewith.

The full lines in Figure 1 illustrate the propeller support 68 as being disposed to operatively position a marine propeller. The support extends between the spaced arm portions of the U-shaped member 49 to position the propeller directly rearwardly of the rudder 41. The dotted lines in Figure 1 illustrate the propeller support in the elevated position to properly position an aerial propeller.

Any suitable control (not shown) may be employed for operating the motor 23 and, once the same is energized, it will drive the propeller 71 through the medium of the several inter-meshing gears carried by the idler shafts in the manner described above. Rotation of the propeller, either of the marine or aerial type, will cause the vessel to move forwardly across the water. The relatively great weight of the motor will hold the inner deck or platform 21 in a horizontal position and the side plates 16 and 17 supporting the deck will be held stationary thereby. The outer platforms 30 which support the yoke 39 and U-shaped member 49 will also be held stationary by the motor whereby the rudder and propeller will be securely held to operate in their respective mediums. The manner in which the propeller is disposed directly rearwardly of the rudder 41 will cause the vessel to be readily responsive to any actuation of the pilot wheel 47 whereby the device may be easily guided. The forward motion of the vessel will cause the hull to rotate about the centrally positioned plates 16 and 17 and the greater the speed of the vessel the greater will be the tendency of the hull to rotate. The rotation of the hull will cause the same to lift itself upon the surface of the water in a manner to decrease the resistance thereof and this tendency will become more marked as the speed of rotation of the hull increases. It may thus be seen that the motor may drive the

hull at essentially high speed and that, as the speed increases the hull will tend to rise higher in the water to materially decrease the head and drag resistance. Obviously, the hull may be of any selected size and passengers and freight may be readily accommodated on the inner platform 21.

Attention is now directed to Figures 5 through 9 wherein is illustrated another form of my invention. In this form of the invention, the nacelle 80 is suspended between a pair of buoyant drums 81 and 82. The nacelle is formed of sheet metal or any other suitable material and constitutes a hollow shell or hull in which the operator of the device sits and in which the driving motor 83 is mounted. As best illustrated in Figure 7, the nacelle is formed with a transverse vertical partition wall or bulkhead 84 to divide the same into the forwardly located operator's station 85 and the rearwardly located engine room 86. I prefer that the bulkhead be suitably fashioned to provide a seat 87 on which the operator may sit. The top of the nacelle forwardly of the bulkhead is cut away and this opening is closed with a cowling 88 the rearward end of which is hingedly connected to the nacelle as at 89. It will easily be seen that the cowling may be raised or lowered to suit the particular condition and that the operator may easily have access into the nacelle through the opening closed by the cowling. The portion of the hull immediately forwardly and below the cowling is bent inwardly and downwardly to form an instrument panel 90 and a depending apron 91 which forms a support for the steering wheel 92. The shank 93 of the steering wheel extends forwardly through the apron and the distal end thereof is suitably held by a bracket 94. The steering wheel is thus freely rotatable in any direction, for the purpose of steering the vessel.

The nacelle is suspended between the rotating drums 81 and 82 by means of a transversely extending tubular axle member 95. The axle member is located adjacent the top of the nacelle and slightly rearwardly of the cowling opening. It extends entirely through the nacelle and the opposite ends thereof project substantially beyond the side thereof to receive the drums. The bearings 96 are mounted in the side walls of the nacelle and between the braces 97 and 98, which braces encircle the nacelle at substantially its middle and which brace 97 constitutes a support for the bulkhead 84. The bearings are in the nature of a tubular portion 99 which extends through the wall of the nacelle and receives the extending end of the axle member 95 the inner wall thereof being circumferentially spaced from the axle member and the said axle member being held centrally located in the sleeve portion 99 of the bearing by means of the braces 100. Each of the bearings 96 is formed with a radial flange 101 which presses against the outer side of the nacelle and is fixedly secured thereto as by welding or the like. Rotatable sleeves 102 extend centrally through the drums 81 and 82. Each of the drums comprises spaced parallel circular side walls 103 and 104 connected by a peripheral band 105. The inner and outer ends 106 and 107 of the sleeve 102 extend through the respective inner and outer walls 103 and 104 of the drums the same being held in fixed association therewith by means of the annular retaining bands 108 welded or otherwise fixedly secured thereto and to the inner side of the side walls of the drums. As best illustrated in Figure 6, the inner

ends 106 of the sleeve extend through the bearing 96 in the side wall of the nacelle. The inner ends of the sleeve terminate in an outwardly extending radial lip 109 which abuts against the inner end of the bearing. An annular lip 110 formed on each of the sleeves between the nacelle and the drum abuts against the outer end of the bearing 96 and against the outer end of the inner member 108. The lip 110 prevents the sleeve from sliding inwardly into the nacelle and also prevents the drum at the outer side thereof from shifting along the sleeve in the direction of the nacelle. It will be readily observed that while the sleeves 102 are of smaller diameter than the bearing 96 they are of substantially larger diameter than the axle member 95 whereby to permit the drum to rotate freely about the extending ends of the axle without frictional engagement between the sleeves and the ends of the axle.

One leg of an L coupling 111 is fixedly secured to the outer ends of the axle member 95. The connecting legs of the couplings are formed with an annular recess 112 which seats the outer end of a respective one of the sleeves 102. It should be noted that the outer end 107 of the sleeves are rotatably seated within the grooves so that upon rotation of the drum the outer end of the sleeves will rotate within the grooves 112 and the inner ends thereof will rotate within the bearings 96. Each of the L couplings is formed with a removable plate 113 which permits access to be easily had to the chamber 114 without removing the coupling from the axle. The L shaped tubular members 115 have one end thereof securely received within the other leg of the couplings 111. Each of the members 115 extends rearwardly of the device and with the leg 116 thereof disposed in laterally spaced relation with the adjacent drum and with the leg 117 thereof arranged in substantially spaced relation with the periphery of the drum and extending inwardly in the direction of the nacelle. The ends of the arms 117 of the tubular members 115 terminate in aligned relation but spaced a substantial distance apart to support the rudder 118 therebetween.

The rudder comprises a supporting frame 119 which connects with the ends of the tubular members 115 and includes upper and lower bars having centrally located bearings 120 in which the rudder shaft 121 is mounted for rotation. The rudder shaft extends substantially below the frame and the rudder 122 carried by the downwardly extending portion projects rearwardly. The portion of the rudder shaft extending between the bars of the frame 119 fixedly carries a quadrant 123.

As hereinabove described the vessel is steered by means of the wheel 92, the portion of the steering shaft extending between the apron 91 and the bracket 94 being provided with a drum 124 about which the steering cable 125 is spirally wound. The cable extends in opposite direction from the drum 124 behind the apron 91 to the pulleys 126 secured to the side wall of the nacelle. The ends of the cable are reeved through the pulleys 126 and pass along the inner walls of the nacelle to a point rearwardly of the bulkhead 84 and directly below the axle member 95. At this point the cables are reeved through the pulleys 127 and passed upwardly and inwardly to the pulleys 128 mounted in slots in the underside of the axle member. It will be remembered that the axle member is tubular and the ends of the cable extending within the same are passed out-

wardly through the drums 81 and 82 and into the chamber 114 in the couplings 111. Pulleys 129 are mounted within the chamber and the cable ends are reeved thereabout and passed through the tubular members 115. The ends of the steering cable extending from the tubular members 115 are wrapped around the quadrant 123 of the steering apparatus. The cable is preferably maintained in a reasonably taut condition at all times so that the rudder will respond immediately to movements of the steering wheel 92. It will be readily apparent that if the steering wheel is moved in one direction the cable will wind about the drum 124 at one end and unwind therefrom at the other end whereby to permit the cable to shift within the several supporting members to effect locking movement of the rudder about the rudder shaft.

I propose to drive the vessel by means of an internal combustion engine 83 mounted on supporting members 130 and 131 of the internal framework of the nacelle. As is best illustrated in Figures 7 and 8 the supporting members 130 and 131 are disposed in close proximity to the bottom of the nacelle whereby to position the relatively heavy engine as far below the axle member 95 as possible. I rely considerably upon the weight of the motor to hold the nacelle in a stationary condition at all times and have found that the weight of the motor is generally sufficient to hold the nacelle steady although if necessary suitable ballast or the like may be suitably placed therein. The drive shaft of the engine extends through the side wall of the nacelle and the extending end thereof carries a drive pinion 132. The drive pinion is in mesh with the relatively large external ring gear 133 fixedly secured to the inner wall of the drum 181. It may thus be seen that actuation of the engine 83 will effect rotation of the drive pinion 132 which will in turn drive the ring gear to rotate the drum 81. In order that the vessel operate properly it is necessary that both of the drums work in unison and I have therefore connected the drums by means of a plurality of circumferentially spaced angle members 134. By reason of the fact that the drums are substantially larger than the nacelle the angle irons may pass around the nacelle during the rotation of the drums without contacting or in any way interfering with the proper operation of the device. As best illustrated in Figures 5 and 7, one web of the angle iron is welded or otherwise fixedly secured to the peripheral strip 105 of the drums and the other web thereof extends radially upwardly from the drums to comprise a blade or paddle.

I have provided braces 135 which extend rearwardly of the vertical brace 98 slightly above the internal combustion engine 83. A guide rod 136 is suspended between the braces 135 immediately rearwardly of the engine 83 and the gas tank 137 is shiftably mounted on the rod. The tank is connected to the engine by means of a flexible tube 138 and it may be fixedly secured to the guide rod 136 at a selected adjusted position therealong. The reason for shiftably mounting the gas tank is to permit the nacelle to be properly balanced at all times. The gas tank may be adjusted on the guide rod to compensate for

any particular weight in the operator's compartment or to compensate for varying loads in the engine room 86. Access to the engine room is had through the trap door 139 and it will be readily observed that the gas tank is conveniently located immediately below the door when it is desired to fill the same.

The operation of this form of the invention is substantially similar to the form first described. 10 When the engine 83 is being operated both of the drums 81 and 82 will be driven in unison and in the same direction. When the device is at rest it will settle in the water to substantially the line 140; however, as soon as the drums begin to rotate and the device begins to move forwardly in the water the drums will lift themselves on to the surface of the water whereby to support the nacelle above the water and to materially decrease the resistance or drag. Obviously as in 15 the case of the first form of the invention the tendency of the drums to lift themselves out of the water will be markedly increased as the speed of the vessel increases.

It is to be understood that the forms of my invention, herewith shown and described, is to be taken as a preferred example of the same and that various changes in the size, shape and arrangement of parts may be resorted to without departing from the spirit of my invention, or the 20 scope of the appended claims.

Having thus described my invention, I claim:

1. A marine vessel comprising a nacelle, hollow axles projecting from the opposite sides of the nacelle, a buoyant drum mounted for rotation 35 on each of said axles, a drive means carried by the nacelle for rotating said drum, an essentially U-shaped tubular frame carried by the axles and extending rearwardly around the rear end of the nacelle, a rudder mounted on the U-shaped frame, and wires operated from within the nacelle and extending outwardly through the axles and through the tubular frame and connected to the rudder.

2. A marine vessel comprising a nacelle, hollow 45 axles projecting from the opposite sides of the nacelle, a buoyant drum mounted for rotation on each of said axles, a motor within said nacelle, a gearing driven by the motor for rotating said drums, an essentially U-shaped tubular frame carried by the outer ends of the axles and extending along the sides and around the end of the nacelle, a vertical bearing carried by the U-shaped frame, a rudder mounted in said bearing, and wires operated from within the nacelle 50 and extending outwardly through the axles and the tubular frame and connected with the rudder.

3. A marine vessel comprising a nacelle, hollow axles projecting from the opposite sides of the nacelle, propeller means mounted for rotation on 60 each of said axles, a drive means carried by the nacelle for rotating the propellers, an essentially U-shaped tubular frame carried by the axles and extending along the sides and around the rear end of the nacelle, a rudder mounted on the U-shaped frame, and wires operated from within the nacelle and extending outwardly through the axles and the tubular frame and connected to the rudder.

RICHARD W. DAVIS.
